CONVERTIBLE PLAY BOX

Richard G. Bock, Chicago, Ill.

Application November 1, 1933, Serial No. 696,137

12 Claims. (Cl. 46—37)

This invention relates to improvements in a convertible play box.

One of the problems constantly confronting parents and teachers of younger children is that of developing a program of properly directed and controlled indoor play which will provide not only a variety of amusement but at the same time develop a certain amount of skill and dexterity and impart information of an educational character. A second problem is to inculcate in children a proper regard for the care of their toys and playthings and, particularly, to put them away at the end of the play period in their proper places and manner so as to avoid leaving the toys and playthings lying around indiscriminately. A third problem frequently arises when parents take their children away from home on visits for any length of time and are under the necessity of providing proper amusement and occupation for their children while away from home in strange surroundings where the usual toys and playthings of the children are generally not available and it is inconvenient or impractical to take a number of loose and miscellaneous toys with one.

One object of this invention is to provide what may be termed a convertible combination playroom, container or receptacle, and play device of neat and attractive appearance, of compact arrangement and suitable for taking from one place to another.

Another object of the invention is to provide a convertible play box, preferably in the form of a small suit case when completely assembled and within which may be compactly stored a wide variety of play things, the box or container being of such character that the several parts thereof may be detached and assembled with each other in several different ways to afford a variety of play occupations for a child, some of the arrangements affording opportunity for developing certain manual skill and dexterity of the child, others to develop strictly educational values, and others musical appreciation.

Still another object of the invention is to provide a convertible play box for neatly retaining a wide variety of play things, the arrangement being such that, in storing away the play things within the box and assembling the box parts, a sense of neatness, orderliness and pride of possession will be inculcated in the possessor thereof.

Other objects of the invention will more clearly appear from the description and claims herein-after following.

In the drawings forming a part of this application, Figure 1 is a perspective view of the im-

proved play box shown assembled and with the various toys and play things assumed to be assembled therein. Figure 2 is a perspective view showing one converted rearrangement of the several box parts. Figure 3 is a vertical sectional view corresponding to the section line 3—3 of Figure 2. Figures 4 and 5 are other perspective views showing still different converted rearrangements of the several box parts to provide other games and forms of amusement for the child. Figure 6 is a transverse, sectional view of the box with all of the parts assembled and showing more particularly the manner of retaining the several parts in the complete assembled box form. Figure 7 is an inside end elevational view showing certain details of construction. And Figure 8 is an inside elevational view of the permanent top of the box to illustrate certain details of construction that cooperate with features of one of the removable or detachable parts.

In said drawings, the convertible play box is shown of generally rectangular form to simulate a suit case and, for convenience of handling, is provided with a hand grip 10 on the top thereof. For convenience of description and not by way of limitation, the box may be said to comprise a top 11, an end 12, a side 13, a two part end 14—15, best seen in Figure 6, a detachable bottom 16, and a detachable side 17. As will be appreciated, the terms top, bottom, sides and ends are more or less relative, dependent upon the position assumed by the box.

In carrying out the invention, the box is made in three separable parts or sections. One part constituting what may best be termed the main part, comprises the side wall 13, top wall 11, and end wall 12, all of which are rigidly and permanently united and, in accordance with the rectangular formation of the box, are disposed in three planes at right angles to each other. Preferably, also, the half 15 of the other end wall is made permanently associated with the main part, just described.

The second detachable part of the box consists of the side 17, the details of which are described hereinafter, and the third detachable part consists of the bottom wall 16, which preferably has rigidly united therewith and extending at right angles therefrom the other half end 14 of the box. In order to carry out certain of the rearrangements of the box parts as, for instance, the set-up shown in Figure 4, the width of the side walls 13 and 17 and more particularly the detachable side wall 17, is made approximately twice the width of the ends of the box so that,

in the arrangement shown in Figure 4 for instance, where the detachable side wall 17 is shown disposed within the main part at one end thereof so as to elevate the latter, said elevated end will 5 be approximately twice the distance above the floor as the lower end of the main part and the latter at the same height as the elevated end of the detachable bottom 16 when the latter is positioned as shown, so as to provide an inclined 10 continuous runway from the highest end of the main part of the box to the lowest end of the bottom 16.

The several parts may be made of any suitable material but, preferably, of as light construction 15 as possible, consistent with the necessary strength. Preferably, each of the walls proper is made of a suitable composition board of heavy card-like nature, as indicated at 20 in Figure 6, the walls proper being suitably rigidified by wood 20 strips around the edges and by which the parts may be neatly held together by suitable nailing, certain of said wood strips as hereinafter described, being so formed and positioned as to perform certain functions in the cooperation of 25 the several parts.

In the case of the main part 11—12—13, edge strips are applied on the outer side thereof as indicated at 21—22—23—24—25 and 26. The strip 21, as best shown in Figures 2 and 4, is beveled at its end as indicated at 121 so as to enhance 30 the support of the lower end of said main part when occupying the position shown in Figure 4.

The detachable side 17 has applied thereto around three of its edges, the strips 27—28 and 35 29 so that, when occupying the position on the floor as best shown in Figure 5, said strips provide a retaining wall or enclosure for marbles or the like that may be rolled down thereonto, one such marble being indicated by dotted lines 40 at 30 in Figure 5. Also, the detachable side wall 17 is provided on the same side as that on which the strips 27—28 and 29 are located, with two additional strips 31—31 arranged parallel with each other and the side strips 27 and 29 and 45 spaced from the latter a distance so as to properly receive and retain between each strip 31 and adjacent side strip, blocks such as indicated at 32—32 in Figure 2, in which arrangement the side wall 17 is functioning as an inclined table 50 or support, as will be apparent. On its under side as it appears in Figures 2, 3 and 5, the detachable side wall 17 will preferably have its surface 171 covered with black board composition so that, when it is reversed as shown in Figures 2 and 3, 55 said wall 17 will provide a convenient inclined blackboard for the child to write or draw upon with chalk.

The third detachable part or bottom 16, is provided on its exterior surface with two longitudinally extending strips 33—33 which, when said bottom 13 is in either of the arrangements shown in Figures 4 and 5, constitute guideways or retaining guides for any articles rolled theredown. In the arrangement of Figure 4, suitable wheeled 60 toys such as miniature automobiles, aeroplanes and the like may be rolled down the incline and onto the floor. In the Figure 5 arrangement, marbles will preferably be rolled down the inclined bottom wall 16 and to provide a game 65 and develop skill of the child, a detachable notched barrier 34, as shown in dotted lines, may be employed so that marbles rolled down may only pass the barrier if skillfully directed to pass 70 through the notch therein. In this latter arrangement, it will be evident that the strips 33

of the bottom 16 are somewhat closer spaced than the strips 31 of the detachable side 17 so that no interference will be provided by the latter for articles rolled down the bottom 16.

Said bottom 16 on its inner side is provided with two additional strips 35—35 flush with the edges of the wall board proper 20 and the half end 14 associated with said bottom 16 is also provided on its inner side thereof with strips 36—36, which are extended beyond the edge 141 of the half end, as indicated at 136—136 where the same butt the ends of two strips 37—37 on the inner side of the other half end 15, which is rigidly associated with the main part of the box. Said half end 15 also has secured to its inner face, and preferably centrally thereof, a strip 38 which is extended beyond the edge 141 so that, when the two half ends are brought together as shown in Figure 6, a rigid joint is provided, the two half ends being retained in assembled position by any suitable means such as the hook and eye 39—40, as shown. In this connection, it will be understood that at the time the hook is latched with its eye, the detachable side wall 17 will be off.

To rigidify the connection between the half end 14 and bottom 16 and also to serve certain other functions, diagonal braces 41—41 are employed, the lower ends thereof, as viewed in Figure 3, being united to the half end 14 at the 105 outer edge of the latter and being extended upwardly to near the top of the bottom 16 and secured to the wall board thereof, as indicated at 141.

Cross braces 42—42 are extended between the 110 main braces 41 on the undersides of the latter, said cross braces 42 being utilized to support a small xylophone framework 43, the metal keys of which are indicated at 44. With this construction, as will be apparent, when the bottom 16 is detached and laid on its bottom wall 16 proper, the xylophone is available for use by the child. Referring more particularly to Figures 3 and 8, it will be noted that the main part of the box is provided with an interior, 120 longitudinally extending strip 45 in the lower righthand corner running lengthwise of the top 11. Said strip 45 as shown, is recessed as indicated at 145 so as to receive therewithin the extended ends 136—136 of the strips on the half 125 end 14 associated with the bottom 16 when the parts are arranged as shown in Figures 2 and 3, thus interlocking said bottom part 16 with the main box part to thus provide a rigid backing or support for the detachable side wall 17 when 130 it is positioned as shown in Figures 2 and 3. In this arrangement, the lower edge of the side wall 17 is supported at its ends on the interior strip 37 of the half end 15 and on the interior strip 46 of the end 12, constituting a part of 135 the main box part. As shown in Figure 2, the end strip 24 is notched, as indicated at 47 so as to allow the insertion therethrough of a corner of the side wall 17 so as to be supported on said strip 46. In this connection, it is evident 140 that the outside longitudinal strip 21 on the top 11 of the main part will serve as a retainer to prevent the lower edge of the side wall 17 from slipping outwardly and hence permit the child 145 to bear with pressure on the sloping side wall, either for the purpose of positioning the blocks 32 thereon or in using chalk in the event the side wall 17 is reversed to present the blackboard side uppermost.

To provide for interlocking the detachable side 17 and detachable bottom 16 with the end 12 of the main part, when the box is to be completely assembled, a horizontal groove 48 is provided by the two strips 24 and 46 to receive the plain edge 271 of the detachable side 17 and a vertically extending groove 49 is provided by the strip 25 on the end 12 and an interior strip 50 to receive the edge 261 of the detachable bottom, 10 as best shown in Figure 7. In assembling the box parts, the combined bottom 16 and half wall 14 are put in place with the edge 261 in the groove 49 and then the half end 14 latched with the other half end 15 by the hook and eye 39-40. 15 After the loose toys and playthings have been inserted within the box, the side wall 17 is next applied by seating the edge 271 thereof within the groove 48 and the side 17 then latched to the half wall 15, forming a part of the main part 20 of the box as by the flat latch 51 and eye 151, in which condition all of the box parts are then held rigidly together and the box as an entirety may be conveniently carried from place to place. The inner face of the side 13 constituting a 25 portion of the main part of the box, is preferably provided with a relatively thick layer 60 of fibrous material so that the same may be used to receive the projecting ends of any nails that may be driven through a piece of wood supported thereon and thus prevent driving nails into a floor. Also, said fiber layer 60 may be utilized for retaining the wickets and stakes of a miniature croquet set, the material being such that the ends of the wickets and stakes may be inserted 30 readily therein and will be held in place, thus adding another game that may be played by the child.

In outfitting the play box, the same will be equipped with suitable hammers for the xylophone; wheeled toys such as automobiles, aeroplanes and the like for use when the box is set up as shown in Figure 4, marbles or other spherical objects for use when the set-up shown in Figure 5 is employed; blocks for use when the box is set up as shown in Figure 2; and chalk for use in connection with the blackboard of side 17. In addition, numerous other toys or play articles may be included in the set such as hammer, nails and a loose nail board; rings and ring posts; ten pins and balls; animals on wheels and various other articles that will readily suggest themselves to those skilled in the art. In connection with the rings and ring posts, the ring posts may be permanently fastened to the 45 inner side of the top wall 11 and the main part of the box set up on said top resting on the floor, in which case the remaining walls of said main part will be upstanding vertically and form a semi-enclosure for the rings as thrown, as will be understood.

From the preceding description, it will be seen that all of the articles of play may be compactly stored within the one box or container; a wide variety of uses may be made of the box parts in the playing of different kinds of games; that the child will necessarily develop considerable skill and dexterity in disassembling the box parts and reassembling them in different arrangements; and in general, will be provided with a wide range of amusements to maintain interest for considerable periods of time.

Although the preferred embodiment of the invention has herein been shown and described, nevertheless the same is susceptible of various changes and modifications and all changes and

modifications are contemplated that come within the scope of the claims appended hereto.

What is claimed is:

1. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter whereby, when positioned with said supporting section down and resting thereon and its opposite end, said bottom provides an inclined runway and, when assembled with said main part, and detachable side, completes the closed box; and means for retaining said main part, detachable side and bottom in assembled condition. 80
2. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said supporting section substantially equaling in length the width of the top of the main part, whereby said bottom may be positioned at an inclination constituting a continuation of the side of the main part when the latter has one end thereof elevated. 95
3. In a convertible play box of the character described, the combination with a main part including a side, end and top rigidly united and respectively disposed in three planes at right angles to each other; of a detachable side; a detachable bottom, the latter having a supporting section at right angles to the bottom proper at one end of the latter, said bottom having guide rails extending lengthwise thereof on its outer surface. 100
4. In a convertible play box of the character described, the combination with a main part including a side, end, and top, all rigidly united; of a detachable side having retaining rails around three edges thereof on one surface; a detachable bottom having a supporting section at right angles thereto at one end thereof; and means for retaining said main part and detachable side and bottom in assembled box form. 110
5. In a convertible play box of the character described, the combination with a main part including a side, end, and top rigidly united and respectively disposed in three planes at right angles to each other; of a detachable bottom, the latter having a supporting section at right angles to the bottom proper at one end of the latter, the length of said supporting section corresponding substantially to the width of the top of the main part and said detachable side being of substantially twice the width of said top, said detachable side being insertable on edge within one end of the main part and the detachable bottom adapted to be positioned in abutting relation with the opposite end of said main part whereby to provide a continuous inclined runway inclusive of the main part and bottom. 120
6. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said main part being provided 130
7. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said main part being provided 135
8. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said main part being provided 140
9. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said main part being provided 145
10. In a convertible play box of the character described, the combination with a main part including a side, end, and top rigidly united and respectively disposed in three planes at right angles to each other; of a detachable side; a detachable bottom, the latter having a supporting section at right angles to the bottom proper at one end of the latter, said main part being provided 150

on the interior thereof with an overhanging shoulder beneath which the free end of said supporting section of the bottom is adapted to engage and be interlocked therewith to thereby provide 5 a backing support extending above said main part.

7. In a convertible play box of the character described, the combination with a main part including a side, end, and top rigidly united and 10 respectively disposed in three planes at right angles to each other; of a detachable side; a detachable bottom, the latter having a supporting section at right angles to the bottom proper at one end of the latter, and a diagonally extending 15 brace between the end of said supporting section and the bottom proper.

8. In a convertible play box of the character described, the combination with a main part including a side, end and top rigidly associated; 20 of a detachable side provided on one side thereof with rails and on the other with a blackboard surface; and a detachable bottom adapted to be supported on end within said main part, said bottom and main part having cooperable means 25 for retaining the bottom in its said on end position, the detachable side with either surface up being adapted to be supported along one edge on said main part and along its other edge against said upstanding bottom.

30 9. In a convertible rectangular play box of the character described, the combination with a main part including a side, one end, another half end, and a top all rigidly associated; of a detachable side; and a detachable bottom having a complementary half end rigid therewith, the width of the 35 ends being substantially half the width of the sides, the detachable side being insertable with

one of its longitudinal edges within one end of said main part to support that end elevated with the other supported on its said half end, and the detachable bottom being supportable on its half end against the lower end of the main part whereby to provide an inclined continuous runway of a length equal to the sum of the lengths of a box side and bottom. 80

10. A play box in accordance with claim 9 wherein said main part and detachable side and 85 said main part and detachable bottom are provided with cooperating interengaging retaining formations when in assembled complete box form.

11. In a convertible rectangular play box of the character described, the combination with a main part including a side, one end, another half end, and a top all rigidly associated; of a detachable side; and a detachable bottom having a complementary half end rigid therewith, said half end of the detachable bottom and the interior of the main part being provided with 90 cooperable interlocking formations and said main part being provided also with additional shoulders to support one edge of said detachable side when positioned exteriorly of said main part and, in 95 part supported by said detachable bottom while the latter is interlocked with said main part. 100

12. As an article of manufacture, a member adapted to constitute a detachable wall of a complete convertible box, said member at one end thereof having a supporting section extending at right angles to the member proper, said section having means adapted to cooperate with corresponding means of another part of the box to provide an interlock to maintain said member proper 110 in a vertically extending position. 110
